UNITED STATES PATENT OFFICE

2,043,600

PRINTING MACHINE

Edward J. Ward, Brooklyn, N. Y.

Application December 12, 1929, Serial No. 413,609

22 Claims. (Cl. 101—96)

This invention relates to an improvement in printing machines of that type adapted to simultaneously print words and figures denoting the same amounts and in which depressible keys of different values are employed to control mechanism adapted to turn parallel rolls on which the letters forming the words and the figures for the printing operation are arranged.

The primary object of the invention is the provision of longitudinally movable bars provided with racks to actuate the letter-bearing and figure-bearing rolls, with said bars normally tensioned for actuation but held against actuation and released to the influence of their tensioning means through the depression of a key, with the said key designed not only to release a particular bar for movement but to predetermine the limit of movement of that bar to thereby predetermine the extent to which the type-carrying rolls are operated, whereby the key will select the type on the particular rolls which is to be arranged in printing position.

The invention has for a further object the provision of means whereby, on the depression of a key in any particular column of keys, all bars to the right of that column of keys will be permitted a movement necessary to actuate their particular type-bearing rolls to indicate zero, so that in arranging for the printing of a particular number, the final figures of which are represented by zero, it is only necessary to depress a number key in the particular number column to actuate all of the bars to the right of that column to a position to move the type-bearing rolls to indicate zero; that is to say, where the type-bearing rolls are to be set to print, for example, \$4,000.00, the key bearing the number "4" in the thousands column is depressed, releasing the particular bar controlled thereby to position the type-bearing rolls corresponding to the thousands column to indicate the numeral "4" as well as the word "Four", whereupon the bars controlled by the hundreds, tens and units columns automatically move to a position to adjust the type-bearing rolls controlled thereby to indicate a cypher on the number-bearing rolls and a blank space or asterisk on the word-bearing rolls.

A further object of the present invention is the provision of a platen or printing head removably connected to the frame of the machine and carrying rolls to force the material on which the imprint is to be made into contact with the type-bearing rolls as the latter may be adjusted in the actuation of the keys, the pressure rolls

of the printing head being movable in one direction to cause an imprint of the type on the paper and movable in the opposite direction in a plane beyond the possibility of imprint pressure, the pressure roll being positively driven in both directions in movement of the main operating handle.

A further object of the invention is the provision of sectors bearing the words "Thousand" and "Hundred", which sectors are automatically moved to printing position on the operation of a key in the thousands or hundreds column, aligning of course with the type-bearing roll on which the selected amount appears as a word, so that in arranging the printing mechanism to indicate the amount of \$4,000.00, the depression of the key bearing the numeral "4" in the thousands column will move the printing roll bearing the word "Four" into a position to arrange that word in the printing line and simultaneously move the sector bearing the word "Thousand" in printing alignment with the word "Four", so that the word imprint will read "Four thousand" by the mere depression of a single key.

A further object of the present invention is the provision of resetting mechanism operated directly by the main operating handle and serving to automatically reset all previously operated bars, the resetting operation taking place simultaneously with the idle or return movement of the pressure rolls of the printing head.

The invention is illustrated in the accompanying drawings, in which:

Figure 1 is a view in longitudinal section, partly in elevation, of the improved machine.

Figure 1' is a detail in elevation showing the means for operating the printing head controlling shaft by the handle.

Figure 2 is a side elevation thereof.

Figure 3 is a rear elevation thereof.

Figure 4 is a broken horizontal section illustrating more particularly the relation of the type-bearing rolls and the printing head.

Figure 5 is a broken sectional view showing the means for operating the word-bearing sectors.

Figure 6 is a perspective view of the operating means for said sectors.

Figure 7 is a sectional view, partly in elevation, showing the connection between the main operating handle and the printing head.

Figure 8 is a sectional view illustrating the means for controlling the imprint position of the pressure rolls of the printing head.

Figure 9 is a perspective view of the control member for the pressure rolls.

Figure 10 is a diagrammatic view showing the development of all of the printing rolls.

Figure 11 is a longitudinal sectional view, partly in elevation, showing the mounting and driving means for the rolls, the rolls being shown diagrammatically without regard to proportions.

Figure 12 is a broken longitudinal section, partly in elevation, showing the pinions operated by the rock bars and the gears for simultaneously driving the selected rolls.

The printing elements of this invention include the printing rolls bearing the words indicating the desired amount and printing rolls bearing the numbers. Each word-bearing roll has a corresponding number-bearing roll and the word-bearing rolls are arranged to permit the printing of the amount in words on a line across the face of a check or the like while the number-bearing rolls are grouped to print the amount in figures at one side of and preferably above the line bearing the amount in words.

The printing head comprises a frame structure including upright side pieces 1 connected by an intermediate frame 2 of appropriate configuration to support the various instrumentalities associated with the printing elements. Mounted in the side pieces 1 is a fixed spindle or shaft 3 on which are supported the word-bearing rolls.

The particular machine illustrated is adapted to indicate amounts up to \$20,000.00, both in words and figures, and while the description of the particular rolls will be in accordance with this arrangement, it is, of course, apparent that the machine may be readily adapted, merely by appropriate duplication, for higher amounts.

The word-bearing rolls are shown as grouped in accordance with United States currency, that is, there will be two rolls which, through proper manipulation, can be caused to indicate the cents from "One" to "Ninety nine", the rolls indicating the dollars from "One" to "Nine hundred and ninety nine", and a single roll indicating the thousands from "One" to "Twenty." The two rolls for indicating the cents are shown at 4 and 5, the three rolls for indicating the dollars are shown at 6, 7 and 8, and the roll for indicating the thousands is shown at 9.

It is, of course, apparent that the rolls 4 and 5 must be capable of printing words to indicate from one cent to ninety nine cents, and unless these rolls are peculiarly constructed, it would apparently require ninety nine separate positions of the rolls for this purpose. To avoid this complication or unusual size, the first roll 4, herein-after termed the units cents roll, presents a series of transverse channels 10 extending transverse the peripheral plane of the roll and each receiving in fixed relation appropriate type members 11 to make up the required word.

In the successive type channels 10 of the units cents roll 4 there is arranged type which, following a proper printing operation of the check writer, will indicate on the check the selected one of the following words: "One", "Two", "Three", "Four", "Five", "Six", "Seven", "Eight", "Nine", "Ten", "Eleven", "Twelve", and the final portions, that is including the final six letters, of the remaining words up to and including "Nineteen", the specific indication on the roll being "irteen", "urteen", "fifteen", "ixteen", "enteen", "ghteen", and "neteen".

Between the final printing designation of "neteen" and the printing designation "One",

there are two blank channels 12 and a channel bearing characters, for example, asterisks 13, which asterisk-bearing channel is the normal printing position of the roll 4 when no cents key has been operated.

The tens cents roll 5, the peripheral surface of which is wider than that of roll 4, is also formed with type-receiving channels 10 which, in sequence, bear the type characters indicating "Twenty", "Thirty", "Forty", "Fifty", "Sixty", "Seventy", "Eighty" and "Ninety", followed by three channels bearing asterisks indicated at 14, and then successive channels bearing portions of the words to make up the completion of the words "Thirteen" to "Nineteen" on the roll 4; that is to say, in these successive channels, the roll 5 bears the characters "Th", "Fo", "F", "S", "Sev", "Ei" and "Ni". Between the "Ni" channel of the roll 5 and the channel bearing the word "Twenty", there is on the roll 5 a blank channel 12, two asterisk-bearing channels 15, and another blank channel 12.

The units roll 6 of the dollars marking rolls is similar to the units roll 4 of the cents marking rolls, that is to say, bears the characters in transverse channels 10 to indicate the words from "One" to "Twelve" and a portion of the words from "Thirteen" to "Nineteen", inclusive, such portions being identical with the similar markings on unit roll 4. The tens roll 7 of the dollars marking rolls bears in transverse channels 10 printing type which indicate the words "Twenty", "Thirty", "Forty", "Fifty", "Sixty", "Seventy", "Eighty" and "Ninety", followed by three channels 16 bearing asterisks, and then successive channels bearing completing portions of the words to match with the incomplete words from "Thirteen" to "Nineteen" on the tens roll of the cents printing rolls.

Following the final partial word on the tens roll 7 of the dollars printing rolls, there is a blank channel 10, followed by two channels 17 bearing asterisks, and a succeeding blank channel preceding the first word "Twenty" on the tens roll 7. In other words, the unit rolls of the cents printing rolls and dollars printing rolls are identical, the tens rolls of these respective sets being also identical.

Preferably the tens roll 5 of the cents printing rolls is somewhat wider than the tens roll 7 of the dollars printing rolls in order to space the words indicating the final dollars reading and the initial cents reading, and if desired, where the space between the final dollars reading and the initial cents reading is of unusual width due to the word being printed, the channel 10 bearing such word may be preceded by an asterisk merely for printing in the blank space and prevent attempted introduction of other matter in a fraudulent manipulation of the check.

The hundreds roll 8 of the dollars printing rolls is formed with the transverse channels 10 and bears type indicating the words "One", "Two", "Three", "Four", "Five", "Six", "Seven", "Eight" and "Nine". The surface of this roll 8 succeeding the final printing space containing the word "Nine" has eleven blank channels 10 followed by two channels 18 bearing asterisks; that is to say, the channels 10 in which printing type are arranged, either asterisks or letters, are equal in number the number of blank channels, so that this roll will print an impression in any position throughout one-half of its peripheral surface, the remaining half of its peripheral surface being blank and without printing effect.

- The thousands roll 9 has transverse channels 10 provided with printing characters successively indicating the words "One", "Two", "Three", "Four", "Five", "Six", "Seven", "Eight", "Nine", "Ten", "Eleven", "Twelve", "Thirteen", "Fourteen", "Fifteen", "Sixteen", "Seventeen", "Eighteen", "Nineteen" and "Twenty", and following the final word "Twenty" there is a transverse channel 19 bearing asterisks, followed by a blank channel. Thus, the thousands roll can print any word from "One" to "Twenty", and also may have a position in which asterisks are printed or a position in which no printing impression is made.
- As the characters printed by the rolls being described are designed to indicate the amount in words, it is, of course, necessary to include in this printing the words "Thousand" and "Hundred" to render legible the amount to be indicated by the words corresponding to the numerals; that is to say if the thousands roll 9 or the hundreds roll 8 of the dollars printing rolls are used, they must be respectively followed by the words "Thousand" and "Hundred" in order to render intelligent the amount printed by these particular rolls. It is, of course, apparent that the printing elements indicating thousands and hundreds will require but two positions, one in which they print the particular word carried by them and the other in which there is no printing of the word; that is to say, if the hundreds roll 8 of the dollars printing rolls is being used, the word printed by it must always be followed by the word "Hundred", whereas if this word is not being used, there will be no necessity for printing the word "Hundred". This applies identically to the thousands roll 9. Therefore, the members used to print the word "Hundred" or "Thousand" need not be rolls as they require but two positions and they are shown as segments having a radius, of course, corresponding to that of the rolls in order that they may lie in the same printing plane as the perforations of the rolls.
- The hundreds segment 26 has radial arms 21 loosely mounted on the spindle shaft 3, the segment bearing on its periphery channels 10 in one of which is arranged type making up the word "Hundred" and in the other of which are a series of asterisks, as at 22. The thousands segment 23 is identical with that of the hundreds segment having arms 21 mounted on the shaft 3, a transverse channel 19 bearing the word "Thousand" and a second channel 24 having asterisk characters arranged therein. Each of these segments 20 and 23 have two limit positions, one in which the asterisks are in the printing line and the other in which the word borne by the segment is in the printing line.
- Means are provided by which the movements of these segments are limited to one or the other of the positions, such means including limiting bars 25 secured at one end to the frame 2 and depending between the arms 21 of the respective segments. These bars have upper and lower projections 26 and 27 to be engaged by a pin 28 projecting from one of the arms 21 of each segment, thus limiting the segment to the upper and lower position determined by the pin and particular projection. The limiting bars 25 also have projections 29 arranged above the segments, between which and the pins 28 are arranged coil springs 30. These springs tend to move the segments with the pins 28 against the upper projections 26 of the limiting bars, this being the nor-

mal position of the segments when arranging the asterisk-bearing channels 22 and 24 in the printing line.

A second spindle shaft 31 is mounted in the side plates 2 in a vertical plane with the spindle shaft 3, this latter shaft bearing the number printing rolls. These number printing rolls are grouped similar to the word printing rolls and as they are designed to print numbers only, they will, of course, occupy very much less space laterally of the head than do the word printing rolls. The cents printing rolls of the number group are arranged substantially in contact, the units roll 32 having transverse channels 33 in the periphery bearing number printing characters in immediately successive groups from "0" to "9", there being two groups of these numbers, the "9" of the final group being separated by two blank channels 33. The tens roll 34 of the cents group of the number printing rolls has its channels provided with number printing characters from "2" to "9" inclusive, followed by ten such channels 33 each bearing a type printing the character "1", and following the final "1" there is a blank channel 33 followed by a channel 35 bearing an asterisk, a succeeding channel carrying a type printing "0", followed by a blank channel 33 between the "0" and the first character "2" before referred to.

The three rolls 36, 37 and 38 printing respectively the units, tens and hundreds of the dollars number printing rolls and the roll 39 printing the thousands of the number printing rolls are grouped together and slightly spaced from the cents number printing rolls. The units and tens rolls 36 and 37 of the hundreds group are identical respectively with the units and tens rolls 32 and 34 of the cents group. The hundreds roll of the dollars print group has its channels 33 provided with number printing characters representing successively the numbers from "0" to "9", following which the succeeding eleven channels 33 of this roll are blank. The next channel, that is the channel immediately in advance of the channel bearing the "0" character, is provided with an asterisk, as at 40. The thousands roll 39 has its successive channels 33 provided with number printing characters from "1" to "20" inclusive and immediately succeeding the character "20" there is an asterisk-bearing channel 41 followed by a blank channel.

The development and correlative positions of the word-bearing rolls and number-bearing rolls are indicated clearly in Figure 10, from which it will be apparent that each of the rolls is shown with twenty-two transverse channels, and, as will later appear, all rolls, when in normal position, present asterisks in the printing line. This is primarily for the purpose of causing each roll, when not in use, to be the means of making an impression on a check, so that substantially the full printing length or space occupied by either the words or numbers will be taken up by a printed character in order to avoid the possibility of fraudulently introducing other characters into an unmarked space and thus changing the value of the check.

The particular rolls both of the word-printing group and of the number-printing group must, of course, be capable of independent operation in order that any one roll may be set to permit the printing of a desired number. To provide for this result, each roll is mounted upon an independent sleeve and each sleeve is independently 75

driven by the setting mechanism to be later described, it being understood, of course, that the similar rolls of the word-printing group and of the number-printing group are intergeared for similar and simultaneous movement, in order that the word and number printed in any one position may be in accord.

From the above description it will be apparent that there are in the present machine six rolls in each group and to secure a balanced operation and save space in assembly three of the rolls of each group are operated from one end of the respective spindle shafts 3 and 31 and the other three rolls are operated from the opposite end. 10 In providing for this operation, the unit rolls 4 of the word-printing group and 32 of the number-printing group are provided with sleeves 42 and 43 respectively, which sleeves are fixed to the respective rolls and loosely mounted on the respective spindle shafts 3 and 31. Immediately 15 beyond these unit rolls, that is between the same and the adjacent side plate 2, the sleeves 42 and 43 are provided with pinions 44 and 45 respectively. These pinions are geared together 20 through an intermediate idler 46 mounted on a stub shaft projecting from the side plate 2, so that the pinions 44 and 45 and thereby the unit rolls 4 and 31 operate in unison in the same direction and to the same extent.

30 The tens rolls 5 and 34 of the respective groups have sleeves 47 and 48 mounted on spindle shafts 3 and 31 within sleeves 42 and 43, the sleeves 47 and 48 being terminally provided with pinions 49 and 50 immediately beyond and adjacent pinions 44 and 45, the pinions 49 and 50 being connected by an idler pinion 51 on the stub shaft referred to, causing the pinions 44 and 45 and thereby the rolls 5 and 36 to operate simultaneously and to the same extent. The rolls 6 of the word group and 36 of the number group are provided with sleeves 52 and 53 respectively which bear directly 40 upon the spindle shafts 3 within the sleeves 47 and 48 and are terminally provided with pinions 54 and 55 respectively arranged immediately adjacent the pinions 49 and 50, said pinions 54 and 55 being geared by an idler 56 on the stub shaft before referred to.

Thus, the rolls 4, 5 and 6 are mounted on concentric sleeves, each independently movable and each provided with a terminal pinion, the rolls 32, 34 and 36 being similarly mounted on concentric sleeves independently movable and having terminal pinions. The pinions of corresponding rolls of the respective groups are geared together 50 through idlers, so that the similar rolls are compelled to move in the same direction and to the same extent in any operation.

The remaining rolls of each group are connected and mounted for simultaneous operation 550 in associated pairs exactly as are the rolls previously described, except that in this instance the remaining rolls have their sleeves projecting toward the opposite end of the spindle shafts and are geared at such opposite end. Thus, rolls 7 and 37 are provided with sleeves 57 and 58 respectively mounted loosely on the spindle shafts 3 and 31 and extending longitudinally of said spindles toward the end opposite that carrying the pinions of the first three pairs of rolls. These 600 sleeves 57 and 58 have pinions 59 and 60 connected by an idler 61 mounted on a stub shaft projecting from the adjacent side plate 2, so that the rolls 7 and 37 are connected for unitary and similar movement. Rolls 8 and 38 have sleeves 62 and 63 mounted on the respective sleeves 51

and 58 and extending beyond the respective pinions 59 and 60 and provided with pinions 64 and 65 respectively connected by an idler 66 on the stub shaft just referred to. Rolls 9 and 39 have sleeves 67 and 68 mounted on the sleeves 66 and 63 respectively and extending lengthwise the spindles 3 and 31 and provided immediately beyond the pinions 64 and 65 with pinions 69 and 70 connected by an idler 71 on the before mentioned stub shaft.

10 Thus, the similar rolls of the number-printing group and word-printing group are connected for simultaneous and similar movement, so that when any roll is moved to arrange, for example, a number indicating word in printing position, the corresponding roll of the number group will be moved to place the number corresponding to that word in printing position.

15 The idlers referred to are each driven by a toothed wheel 72 and the respective toothed wheels are fixed to sleeves 73, such as previously described, concentrically mounted on a shaft 74. To the inner ends of the sleeves 73 are fixed toothed wheels 75 adapted to be operated by racks 76 which are connected to and form continuations of operating bars 77.

20 Arranged in the machine in advance or forwardly of the printing elements are longitudinal frame bars 78 in which are mounted vertically movable keys 79. The keys are arranged in rows 25 longitudinally of the machine, there being one row for each separate type-bearing roll of the printing elements; that is to say, there are two rows of keys for cents and a row of keys for each of the units, tens, hundreds, thousands, etc., for 30 dollars.

25 A control bar 77 is arranged beneath each row of keys, and the rack 76 of each control bar is pivotally connected to that bar and moves in a guide 80 below the toothed wheels 75, the guides 30 serving to hold the rack in cooperation with its particular toothed wheel. The control bars and racks are pivotally connected one with the other so that while the rack is confined to a sliding movement in a horizontal plane, the control bar 45 proper is permitted a vertical play as well as a sliding movement for a purpose which will later appear.

30 Each rack bar is provided with a depending pin 81 to which is connected one end of a spring 82, the opposite end being anchored to the frame. These springs serve to move any particular control bar and its connected rack toward the rear of the machine when the parts have been actuated to free the control bar from its normal holding means.

35 A leaf spring 83 underlies each control bar to hold the free or forward end of said bar in a raised position to thereby permit a projection 84 on said bar to engage in advance of the lower edge of a transverse frame plate 85. Thus the control bars are normally held against movement in the rearward direction under the influence of the spring 82.

40 Each of the keys 79 is supported by a light spring 86 and each key is adapted, when depressed, to correspondingly depress the underlying control bar 77 to a position to free said bar from holding cooperation with the plate 85 and thereby permit the spring 82 of that bar to move 45 it and the corresponding rack 76 rearwardly for the operation of the printing elements. Each control bar is provided with stops 87 and the lower end of each key is shouldered to provide a portion which will engage and depress the par-

ticular control bar and a portion which will depend in the plane of movement of one of the stops 87.

Quite obviously, therefore, the depression of a particular key will first release the underlying control bar and provide a limit element with which an adjacent stop on the control bar operates when the control bar is moved under the influence of its spring to thereby limit the operative movement of the control bar. If the stops 87 are appropriately arranged, it will be apparent that a particular key will so limit the operative movement of the control bar that the rack of that control bar will actuate the printing rolls to that predetermined extent necessary to arrange in the printing line the word and number corresponding to that of the key depressed. The character of the stops 87 is immaterial as they may be formed as projections, indentations, or in any other desired manner.

It is, of course, apparent that the machine must be so designed that only one key of a particular row may be depressed for any one operation of the machine and that therefore means must be provided whereby, when a particular key has been depressed, all other keys of that row are locked out or prevented from being operated.

To secure this result, a locking plate 88 is arranged for cooperation with each row of keys and mounted for a sliding movement in the frame parts, the plate being held or influenced for movement in the rearward direction by a spring 89. The plate is formed with a series of apertures 90, one for each key and each key is provided with a rearwardly extending projection 91 which, together with the width of the key, presents an area just sufficient to pass through the particular plate opening 90. Above the projection 91 each key is formed to provide a shoulder 92 extending forwardly and above the shoulder the key is of somewhat greater width than below the shoulder.

Therefore, on the depression of any key, the locking plate is moved forwardly against the influence of its spring, and when the key reaches its fully depressed position, the shoulder 92 is on a plane below the locking plate and the latter, under the influence of the spring, moves rearwardly, engaging above the shoulder 92 and preventing the particular key from rising. As the wider portion of the operated key is now in the opening 90 in the locking plate, this locking plate is held in a forward position to a degree insufficient to permit the operated key shoulder 92 from moving upwardly but sufficiently to prevent the projection 91 from passing downwardly through any of the other openings 90 of the locking plate. Thus, the locking plate serves to permit the operation of a selected key; serves to hold that selected key in operated position; and serves to prevent the operation of any other key of the row.

From the above description, it will be understood that when a particular key is depressed it will permit the control bar to move a predetermined distance and that this movement of the control bar will correspondingly move its connected rack and through the rack position the type-bearing rolls controlled by the particular key to arrange the desired printing elements in the printing line.

In connection with the operation of a particular control bar, it is desired that all remaining control bars to the right be permitted an automatic movement to arrange the number-bearing printing rolls of all such control bars to the right to

indicate zero, and as will be plain from Figure 10, to cause all the word-bearing printing rolls to position a line of asterisks in the printing line. This is for the purpose of permitting a number containing one or more zeros as the final digits to be arranged for printing by the depression of only the keys necessary to indicate the selected numbers.

To provide for this, each control bar 77 is provided forwardly of the stop 84 with an additional stop 93, this stop being spaced from the stop 84 a distance equal to the desired movement of the control bar for moving its governed type-bearing printing rolls to the zero indicating position. Each control bar 77 overlies a lateral roller 94 of a lever element 95 pivotally mounted upon the frame bar 85 below the control bar. Each lever element additionally includes an arm 96 overlying a pin 97 projecting from the next adjacent control bar to the right.

Thus, on operation of any one control bar 77, the lever elements of all control bars to the right are tripped and such control bars to the right are depressed to release the engagement of the stop 84 and frame 85, following which depression and incident to the rocking of the lever element 95, the arm 96 rides off of the pin 97. The depression of the particular control bar has been sufficient to permit the spring 82 to move the control bar rearwardly a distance between the stops 84 and 93 and as the arm 96 of the lever element rides off of the pin 97, the springs 83 act to move the control bar upwardly to cause its stop 93 to engage the frame bar 85. Thus, all control bars to the right of the operated control bar will be automatically operated to set the number type-bearing rolls to the zero positions.

It has been previously stated that the segments 20 and 23 bearing respectively the words "Hundred" and "Thousand" are normally positioned so that the words carried thereby are out of the printing line and that such segments or either of them are not to be operated so as to move the particular word into the printing line unless the roll with which the particular segment cooperates is operated. From the previous description, it will be seen that the roll 8 of the hundreds column of the word-printing group is operated through the operation of a particular pinion while the thousands roll 9 is operated through the operation of another pinion.

It is apparent, therefore, that means must be provided which, in the operation of these respective pinions, will also actuate the corresponding segment so as to arrange the word thereon in the printing line; that is to say, when the roll 8 is operated to arrange a word thereon in the printing line, the segment 20 must be operated to move the word "Hundred" thereon into the printing line, so that the word printed will have its proper significance and consequently when the roll 9 has been operated to arrange a word thereon in the printing line, the segment 23 must be correspondingly operated to arrange the word "Thousand" in the printing line.

Loosely mounted between the arms 21 of each of the segments is a collar 98 from which projects an arm 99 connected by a spring 100 to an extension 101 of one of the arms 21. A spindle 102 is mounted in projections from the frame 2 on which spindle is mounted a sleeve 103 having an arm 104 projecting toward segment 20 and terminating in a roller 105 which rests between the arm 99 and extension 101. The opposite end of the sleeve 103 is provided with an arm 106 which

extends toward the spindle and is terminally provided with a roller pin 107 which bears upon an annular flange 108 forming part of the pinion. This flange is of somewhat less diameter than the maximum diameter of the pinion and is concentric with the pinion except for a recess 109 of a size to receive the roller pin 107.

Also mounted on the spindle 102 is a second sleeve 110 having at one end an arm 111 extending toward the segment 23 and terminating in a roller pin 112 bearing between the arm 99 and projection 101 of this segment. The sleeve 110 has a second arm 113 projecting toward the spindle and terminating in a roller pin 114 bearing on an annular flange 115 forming part of the adjacent pinion, this flange being concentric with said pinion except for a recess 116 of a size to receive the roller pin 114. The parts are so designed that when the rolls 8 and 9 are in normal position, that is with no printing indicia on such rolls other than the asterisks in the printing line, the pinions will be in such positions that the roller pins 107 and 114, which control the arms 104 and 111, will be in the respective recesses 109 and 116. Under these conditions, the roller pins 105 and 112 of the arms 104 and 111 will exert no pressure on the segments and the springs 39 will hold the segments in such positions that the words borne thereby will be out of the printing line, that is with their pins 28 against the upper projection 26 of the limiting bar.

In operating either of the rolls 8 or 9, the pinions respectively corresponding therewith must, of course, be first actuated. As these pinions are turned, the roller pins 107 and 114 will be moved out of the recesses and onto the concentric portions of the flange 108 or 115. This causes the arms 104 and 111 to be moved to exert a pressure on the collar arm 99 of the particular segment or and through the spring 100 move the segment or segments so that its pin 28 will be forced against the lower projection 27 of the limiting bar, thus arranging the word carried by the segment or segments in the printing line. Of course, if but one pinion is operated, but one segment will be actuated, though the construction provides for the operation of both segments if both rolls 8 and 9 are to be positioned for printing.

Resetting means for all operated racks and for the simultaneous release of all actuated keys is provided through the medium of levers 117 connected to the frame bars 1 and connected near their lower ends with a cross-bar 118 normally held in their rearmost position by a spring 119. The cross-bars 118 are arranged in rear of the pins 81 depending from each rack, so that when the levers 117 are operated, all pins 81 and thereby all racks which have been moved rearwardly are returned to normal positions, upon reaching which the projections 84 on the returned control bars engage beneath the edge of the opening in the frame bar 85.

A shaft 120 is mounted on the frame adjacent the rear ends of the locking plates 88, from which shaft depends an arm 121 seating in an opening in the rear end of each locking plate. The shaft 120 carries an upstanding rigid arm 122 connected by a cross-bar 123 with one of the levers 117. Thus, as the lever 117 is operated, all locking plates are moved forwardly to release the locked keys, the springs 86 elevating the keys to normal position.

A shaft 124 is supported beneath the bed plate 125 of the machine for rocking movement, one end of the shaft being provided with a handle

126, hereinafter referred to as the main operating handle. A gear segment 127 is secured on shaft 124 extending through a slot in the bed plate 125 at one side of the bank of keys. This segment cooperates with a gear 128 supported upon a shaft 129 mounted in a pillar 130 rising from the bed plate, on which shaft 129 is secured a bevel gear 131 cooperating with a bevel gear 132 arranged on one end of a shaft 133 and extending longitudinally of and toward the rear 10 of the bed plate for the operation of the pressure rolls in a manner which will later appear.

Mounted in the upper surface of the base plate at the forward end is a shaft 134 on one terminal of which is a finger lever 135. On the 15 shaft 134 is a projection 136 adapted, when the shaft is operated in one direction, to force upwardly the forward end of a resetting lever 137 which extends longitudinally of the machine and is pivoted to the frame at 138. The resetting 20 lever has a depending arm 139 in line with the pivot which extends through a slot in the bed plate 125 and is connected to one end of a spring 140 anchored at the opposite end to the bed plate to insure the return movement of the resetting 25 lever. The rear end of the resetting lever 137 is connected to an angle lever 141 pivoted on the frame, one arm of which has a pin-and-slot connection with the cross-bar 123, the relation being such that in the operative movement 30 of the resetting lever, all actuated rack bars are returned to normal position.

Loosely mounted on the shaft 134 is a plate segment 142 which is moved about the shaft as a center through the medium of a bar 143 connected to the gear segment 127 and to the plate segment 142. An arm 144 is secured to the shaft 134 and pivotally carries at its free end a pawl 145, a shoulder 146 at the nose end of which is designed to overlie and rest in the 40 plane of movement of the free end of the plate segment 142.

Thus, when the plate segment is operated under normal or non-repeat conditions in the movement of the main operating handle 126, the 45 shoulder 146 of the pawl 145 is engaged and the shaft 134 moved in a direction to raise the forward end of the resetting lever 137. In this movement, the tail 147 of the pawl 145 engages a stop 148 fixed on a standard 149 rising from the bed plate and trips the pawl to release the shaft 134 and permit the spring 140 to move the resetting arm for the resetting operation.

Obviously, therefore, if the pawl is held so that the plate segment 142 does not engage the 55 same in the operation of the handle 126, the resetting mechanism is not operated. This is taken advantage of to secure a repeat operation, this repeat mechanism including a shaft 150 mounted in the standard 149 and provided at one end with an arm 151 having a pin 152 underlying the pawl. The opposite end of the shaft 150 is connected by a lever 154 to a repeat key 159 arranged in one row of keys, preferably the row nearest to the mechanism being described. 60

The repeat key is formed so as to cooperate with the locking plate 88 of that row of keys but avoids operating the control bar for that row. Thus, when the repeat key is depressed, it does not affect the status of any other key of 70 the row nor induce an operation of the control bar. When the repeat key is depressed, the shaft 150 is rocked, so that the pin 152 underlies the pawl 145 and prevents the shoulder 146 thereof from engaging the plate segment 142. There- 75

fore, the main operating handle may be operated at will without effecting a resetting of the type-bearing rolls from their previously set position. In this way, any particular printing position 5 said rolls may be continuously reprinted on the check or other paper as often as desired. When the repeat key has been restored to normal position, the pawl 145 will be engaged by the plate segment in the next operation of the parts and 10 the resetting operation carried out.

An essential feature of the present invention is the provision of a printing head to be removably secured to the machine proper and to provide for impressing the type of the printing 15 rolls when in printing line onto the check or other article to be printed, the impression being reproduced through an inked ribbon. The printing pressure is obtained through the use of pressure rolls acting only on the printing line, 20 and in order to avoid irregular or smearing impressions, the impression rolls are moved in one direction with imprinting pressure and in the opposite direction without such pressure.

The printing head includes a skeleton frame 25 156 designed to be removably secured to the main frame of the machine, preferably through openings 157 designed to fit over studs 158 on the machine frame, nuts 159 cooperating with the studs to secure the head in proper position. 30 The inner surface of the printing head or that portion next the type-bearing rolls is in the form of a thin plate 160 having transverse slots 161 and 162 arranged in the printing line of the respective sets of type-bearing rolls, the 35 upper slot 161, which is designed to cooperate with the number-bearing rolls, being closed at points at which there are no numbers presented, while the lower slot 162, which cooperates with the word-bearing rolls, is open throughout its 40 whole length.

A guide rod 163 is fixed in ears extending rearwardly from the main frame of the printing head and an impression member 164 is mounted for sliding movement on the guide rod, being preferably formed with an elongated bearing on said rod to insure an easy and accurate movement of the impression member. Upper and lower impression rollers 165 and 166 are supported for free rotative movement in the impression members, these rollers being aligned with the respective slots 161 and 162, so as to force the check or other paper into contact with the type, through the intervening inked ribbon, to impress a particular type onto the check or paper.

55 As previously stated, the impression rollers are designed to act with printing pressure in the movement of the impression member in one direction transverse the head and free of this printing pressure in the opposite direction. To secure this result, the impression rollers are supported upon shafts 167 mounted in elongated openings 168 in inwardly projecting extensions of the impression member, thus permitting the rollers to have movement to and from their impression 60 positions. Springs 169 are arranged in rear of the shafts 167 to normally hold the shafts and thereby the impression rollers in imprinting or pressure positions.

70 U-shaped adjusting members 170 are arranged to cooperate with the shaft of each impression roller, the arms of the members being of tapering form and fitting in correspondingly shaped openings 171 in the roller carrying projections in advance of the shafts 167. The adjusting members 75 170, by reason of their tapered formation and of

the correspondingly tapered formation of the openings 171, are limited in movement in one direction and in this position recesses 172 formed in the arms of the members are aligned with the shafts 167 to permit said shafts to move toward 5 the type-bearing rolls under the influence of the springs 169. In movement in the opposite direction, the members are moved to cause the shafts and thereby the rollers to be forced outwardly from the type-bearing rolls, thus preventing pressure-bearing contact of the rollers. 10

The adjusting members 170 project in both directions beyond the roller-carrying projections of the impression member, and the frame 156 of the printing head presents abutments 173 with 15 which the adjusting members contact as the impression member reaches its limit of movement in both directions, to thereby properly position the adjusting members for controlling the pressure-bearing contact of the impression rollers. 20

The impression member is reciprocated transverse the printing head in the respective movements of the main operating handle, and to secure this result, rollers 174 are rotatably mounted on the printing head beyond the limits of movement 25 of the impression member, one of the rollers being provided with radial projections 175. A band 176 formed with openings to cooperate with the projections 175 encircles the rollers and is secured to the impression member at 177. Thus, with 30 the roller 174, which is provided with the projections, operated in the movement of the handle 126, the impression member will be reciprocated. Of course, it is understood that the openings in the band 176 need not extend throughout the 35 full length of the band but only for the distance necessary to cause the required movement of the impression member.

The roller 174, which is provided with the projections, is supported upon a shaft 178 which extends through the frame 156 and is formed with a diametrically opposed slot 179. The shaft 133, heretofore described as rotated in the operation of the handle 126, is formed with a terminal projection 180 to fit within the slot 179. Thus, when 40 the printing head is in position, the power roller for operating the impression member is directly connected to the shaft 133, so that in the operation of the handle 126, the impression member is reciprocated. 50

It is understood, of course, that an inked ribbon is employed and arranged between the impression rolls and the type of the type-bearing rolls and that this ribbon is intermittently advanced in each idle movement of the impression member. 55 Any conventional means may be employed to this end, the power therefor being taken from the shaft 124, though this detail forming no part of the present invention, is not illustrated.

Furthermore, as in the ordinary machine of 60 this type, means operated by the shaft 124 may be employed to center the printing rolls, such means including members which, following the initial setting of the printing rolls and during the printing operation, may engage in the teeth 65 of one of the sets of gears for operating the printing rolls to absolutely center the gears and at the same time prevent any possibility of their accidental movement during the printing operation.

70 Furthermore, the invention contemplates as a part of the machine, if such be desired, any conventional means for ejecting the printed check or paper. Such means is illustrated conventionally at 181 in Figure 3, but no particular detailed de- 75

scription thereof is necessary as such forms no material part of the present invention.

Through the use of the machine described, it is apparent that through the manipulation of the proper keys, the type-bearing rolls, both as to words and numbers, may be appropriately set. On operation of the main handle 126, a check or paper introduced into the machine will be appropriately printed; the return movement of the handle serving to restore the printing roll to normal position for the next operation. If the particular number and word set is to be repeated on a subsequent check or checks, the repeat key is depressed whereupon, as described, the main operating handle may be actuated for the desired number of printing operations without disturbing the previously set type-bearing rolls.

Of course, the operative parts of the machine, other than the main operating handle 126 and the finger lever 135, are to be enclosed in a suitable casing, though this is not deemed necessary to illustrate.

The finger lever 135, of course, serves to provide for an operation of the resetting mechanism without the necessity of operating the main operating handle 126, provision being thus made for correcting any errors which may arise during the setting of the printing rolls for a particular printing operation.

What is claimed to be new is:

1. In a printing machine including manually operable printing means capable of variable printing positions and an operating handle, an impression head arranged in rear of the printing means, an impression member reciprocated transversely of the head, rollers carried by the member for impression cooperation with the printing means, means carried by the member and automatically actuated in the reciprocation of the member to permit the impression rollers to assume an impression position in one movement of the member and compel said rollers to move to a non-impression position in the other movement of the roller, and means directly operated by the handle for reciprocating the impression head, said means including a band connected to the member, rollers mounted on the head over which the band travels, one of the rollers being designed for driving connection with the band, and a shaft operated by the handle and having a removable connection with the driving roller.

2. In a printing machine, a series of type-bearing rolls, a plurality of rows of manually operable keys, each row of keys controlling two of such type-bearing rolls, means intermediate each row of keys for operating the type-bearing rolls controlled by such row of keys on the depression of any key of the row, and means automatically actuated on the depression of any key of one row to correspondingly and automatically effect a predetermined movement of the type-bearing rolls controlled by the keys of certain other rows.

3. A printing machine including a plurality of sets of type-bearing rolls, the rolls of one set being designed to imprint words and the rolls of the other set being designed to imprint corresponding numbers, a plurality of rows of keys, a control bar operated by each row of keys to compel a simultaneous and similar movement of a particular word-bearing roll and corresponding number-bearing roll, and means whereby the operation of one control bar by a key automatically compels movement of certain other control bars to thereby move the word-bearing and

number-bearing rolls of such other control bars a predetermined distance.

4. A printing machine including a plurality of sets of type-bearing rolls, the rolls of one set being designed to imprint words and the rolls of the other set being designed to imprint corresponding numbers, a plurality of rows of keys, a control bar operated by each row of keys to compel a simultaneous and similar movement of a particular word-bearing roll and corresponding number-bearing roll, and means whereby the operation of one control bar by a key automatically compels movement of certain other control bars to thereby move the word-bearing and number-bearing rolls of such other control bars a predetermined distance, said automatically operated control bars being capable of key-controlled operation independently of the automatic operation.

5. A printing machine including a plurality of sets of type-bearing rolls, the rolls of one set being designed to imprint words and the rolls of the other set being designed to imprint corresponding numbers, a plurality of rows of keys, a control bar operated by each row of keys to compel a simultaneous and similar movement of a particular word-bearing roll and corresponding number-bearing roll, and a lever operated by each key-operated control bar to correspondingly operate the control bar of the next adjacent row of keys to permit a predetermined movement of such bar and a corresponding operation of the word-bearing and number-bearing rolls of that bar, the levers being arranged to operate all control bars which govern word-bearing and number-bearing rolls expressing a lower amount than the rolls operated by the key-actuated control bar.

6. In a check printer or the like, a manually positioned printing roll bearing word indications of a series of numbers, a printing segment bearing a word to complete the indication of the printing roll, means for normally holding the segment out of printing position, and means for moving the segment into printing position simultaneously with the movement of the printing roll to any printing position other than normal.

7. In a check printer or the like, a printing roll bearing word indications of figures, a printing segment bearing a word to complete the indication of the printing roll in any printing position of said roll other than normal, a pinion for operating the printing roll to any printing position, manually operable means for controlling the movement of the pinion and thereby of the printing roll, and means intermediate the segment and pinion and operated in the initial movement of the pinion to move the segment into printing position.

8. In a check printer or the like, a printing roll bearing word indications of figures, a printing segment bearing a word to complete the indication of the printing roll in any printing position of said roll other than normal, a pinion for operating the printing roll to any printing position, manually operable means for controlling the movement of the pinion and thereby of the printing roll, and means intermediate the segment and pinion and operated in the initial movement of the pinion to move the segment into printing position, said means serving to maintain the segment in printing position during any printing roll movement of the pinion.

9. A check printer or the like including a printing roll bearing word indications, a printing segment bearing a word to complete the sig-

nificance of the words on the printing roll, a manually controlled pinion for operating the printing roll to a selected printing position, means for moving the segment into and out of printing position, and an element operating with the pinion to control said means, said element being formed to position the means for holding the segment at the printing position when the pinion and thereby the printing roll is in normal position, the element operating to force said means to move the segment to printing position in any movement of the pinion tending to set the printing roll for printing.

10. In a check printer or the like, a printing roll bearing words, a printing segment bearing a word indication to complete the printed representation of the printing roll in any one printing position, a member for rocking the printing segment to and from a printing position, a manually controlled pinion for selectively operating the printing roll to any printing position, a collar carried by and movable with the pinion and formed with a depression, and a member carried by the rocking element to seat in said depression 25 when the pinion, and thereby the printing roll, is in normal position, the surface of the collar beyond the depression serving to rock the element to move the segment into printing position in any pinion movement tending to position the printing roll for the printing operation.

11. In a check or like printer of the type including a manually controlled printing means and a main operating handle, a printing impression member, a shaft on which the member is guided, means intermediate the member and handle for reciprocating the member on the shaft, impression rolls carried by the member and designed for impression cooperation with the printing means, each of the rolls being mounted on a shaft having a limited free play in the member toward and from the printing means, and an element automatically cooperating with said shaft for moving the shaft and thereby the roll mounted thereon to a position free of the printing means.

12. In a check or like printer of the type including a manually controlled printing means and a main operating handle, a printing impression member, a shaft on which the member is guided, means intermediate the member and handle for reciprocating the member on the shaft, impression rolls carried by the member and designed for impression cooperation with the printing means, each of the rolls being mounted on a shaft having a limited free play in the member toward and from the printing means, and an element automatically cooperating with said shaft for moving the shaft and thereby the roll mounted thereon to a position free of the printing means, said element being formed to permit the shaft in a certain relative position of the element to be free of the holding influence of the element.

13. In a check or like printer of the type including a manually controlled printing means and a main operating handle, a printing impression member, a shaft on which the member is guided, means intermediate the member and handle for reciprocating the member on the shaft, impression rolls carried by the member and designed for impression cooperation with the printing means, each of the rolls being mounted on a shaft having a limited free play in the member toward and from the printing means, an element automatically cooperating with said shaft for moving the shaft and thereby the roll mounted thereon to a position free of the printing means,

said element being formed to permit the shaft in a certain relative position of the element to be free of the holding influence of the element, and spring means cooperating with each shaft to move the shaft and thereby the roll carried on the shaft yielding toward the printing means.

14. In a check or like printer of the type including a manually controlled printing means and a main operating handle, an impression head, a shaft on which the head is guided, means actuated by the handle for reciprocating the head on the shaft, an impression roller mounted in the head for bodily movement in a direction at right angles to the movement of the head, said roller in an operative position cooperating with the printing means and in an inoperative position being held free of cooperation with the printing means, and means automatically set at the respective limit movements of the head in the operation of the handle for controlling the relation of the roller to the printing means.

15. In a check or like printer, an impression head, means for guiding the head for movement in a fixed plane, impression rollers carried by the head above and below said guiding means, mounting means for the impression rollers to permit said rollers to move independently in parallel planes at right angles to the plane of movement of the head, and means carried by the head and automatically operable at the extreme limits of movement of the head for controlling the mounting means.

16. In a check or like printer, an impression head, means for guiding the head for movement in a fixed plane, impression rollers having their axes parallel to the plane of movement of the head, means for mounting said rollers in the head to permit independent bodily movement of the rollers in parallel planes at right angles to the plane of movement of the head, means carried by the head for automatically moving the rollers toward an impression position, and elements carried by the head and automatically reciprocated at the respective limits of movement of the head, said elements in one position holding the rollers against the influence of the automatic positioning means and in another position freeing said rollers to said automatic moving means.

17. In a check or like printer, an impression head, means for guiding the head for movement in a predetermined plane, upper and lower impression rollers carried by the head, with their axes parallel to the plane of movement of the head, springs carried by the head for moving the rollers bodily in a direction at right angles to the plane of movement of the head for impression purposes, elements carried by the head and cooperating with the rollers, said elements in one position freeing the rollers for movement under the influence of the springs and in another position for holding the rollers against such spring-influenced movement, and means arranged at each limit of movement of the head for operating said elements.

18. In a check or like printer, an impression head, means for guiding the head for movement in a predetermined plane, upper and lower impression rollers carried by the head, with their axes parallel to the plane of movement of the head, springs carried by the head for moving the rollers bodily in a direction at right angles to the plane of movement of the head for impression purposes, elements carried by the head and cooperating with the rollers, said elements in one position freeing the rollers for movement under

the influence of the springs and in another position for holding the rollers against such spring-influenced movement, and means arranged at each limit of movement of the head for operating said elements, said elements in each position limiting possible movement of the rollers.

19. In a check or like printer, an impression head, means for guiding the head for movement in a fixed plane, impression rollers mounted in the head, with their axes substantially parallel to the plane of movement of the head, springs for moving the rollers bodily in a plane at right angles to the plane of movement of the head and into impression position, and elements mounted in the head and cooperating with the rollers, said members being movable to different positions during movement of and at the limit of movement of the head in each direction, said elements in one position holding the rollers against spring-influenced movement and in another position freeing the rollers to such spring-influenced movement.

20. In a check or like printer, an impression head, means for guiding the head for movement in a fixed plane, impression rollers mounted in the head, with their axes substantially parallel to the plane of movement of the head, springs for moving the rollers bodily in a plane at right angles to the plane of movement of the head and into impression position, and elements mounted in the head and cooperating with the rollers, said members being movable to different positions during movement of and at the limit of movement of the head in each direction, said elements in one position holding the rollers against spring-influenced movement and in another position freeing the rollers to such spring-influenced movement, the elements in both positions forming a fixed limit of movement of the rollers toward their impression position.

21. In a check or like printer, an impression head, means for guiding the head for movement in a fixed plane, upper and lower rollers carried by the head, with their axes substantially parallel to the plane of movement of the head, springs carried by the head for influencing the rollers to move the rollers in a plane at right angles to the plane of movement of the head and toward and into impression position, and elements slidably mounted in the head and automatically operated at each limit of movement of the head to thereby assume one of two positions during movement of the head, said elements being formed with recesses to align with the axes of the rollers in one position of the elements to permit movement of the rollers under the influence of the springs to the limit of the recesses.

22. In a check or like printer, an impression head, means for guiding the head for movement in a fixed plane, upper and lower rollers carried by the head, with their axes substantially parallel to the plane of movement of the head, springs carried by the head for influencing the rollers to move the rollers in a plane at right angles to the plane of movement of the head and toward and into impression position, and elements slidably mounted in the head and automatically operated at each limit of movement of the head to thereby assume one of two positions during movement of the head, said elements being formed with recesses to align with the axes of the rollers in one position of the elements to permit movement of the rollers under the influence of the springs to the limit of the recesses, said elements beyond the recesses holding the rollers in retracted position relative to their impression position and against the influence of the springs.

EDWARD J. WARD.
